REEL FOR MOVING PICTURE FILMS

Jacob M. Goldberg, Denver, Colo.

Application October 25, 1934, Serial No. 749,896

3 Claims. (Cl. 242—70)

This invention relates to improvements in reels for moving picture films.

For the use with moving picture machines, especially of the type designed for home use, it is desirable to have reels that are light in weight, but which are rigidly constructed, and therefore it is customary to employ aluminum for this purpose. Since aluminum is a soft metal that is not very well adapted to resist severe strains and wear, experience has shown that such reels will wear with exceptional rapidity at the center opening where they are attached to the shaft of the rewind apparatus.

It is the object of this invention to produce a reel construction which shall make it possible to successfully employ aluminum for the greater portion of the reel and to reinforce the aluminum parts with steel plates at the points where the wear occurs.

Another object is to construct a moving picture reel of aluminum and to provide a perforated plate of steel or other wear resisting material so positioned that it will receive the strains and wear due to the action of the rotating driving pin.

Having thus briefly set forth the objects of the invention and briefly described the construction, the same will now be described in detail, and for this purpose reference will be had to the accompanying drawing in which the preferred construction has been illustrated, and in which:

Fig. 1 is a side elevation of the improved reel, on a reduced scale, showing the same fully assembled;

Fig. 2 is a side elevation of the center portion of the reel showing the parts in substantially full size, the outer ends of the spokes and the rim having been broken away;

Fig. 3 is a section taken on line 3—3; Fig. 2;

Fig. 4 is a section taken on line 4—4, Fig. 1; and

Fig. 5 is a section, to a reduced scale taken on line 5—5, Fig. 1.

Each reel consists of two substantially identical side members, each of which has a rim 6, spokes 7 and a center depressed portion 8. The depressed center portions are offset with respect to the surrounding parts of the side members a distance substantially equal to one-half the width of the film and which distance has been designated by reference character a in Fig. 3. When the two side members are connected with the bottoms of the depressed portions in contact as shown in Fig. 3, the side members are spaced a

distance equal to $2a$, which is slightly greater than the width of the film with which the reel is to be employed. The bottom of each depressed area is provided with an opening 9. Located in each of the depressed areas is a hub member or side plate which has been designated by reference numeral 10. The periphery of each hub member, which has been designated by reference numeral 11, is offset with respect to the central portion thereof and the annular surface thus formed 10 rests on the bottom of each depressed area and the two hub members and the side members are secured in assembled relation by means of rivets 12. The central portion of each hub member is offset from the adjacent bottom portion of the 15 depressed area in which it is located and a steel plate 13 is secured to the inside of each hub member 10 in the manner shown in Fig. 3. The steel plates 13 are held in place by means of rivets 14.

In order to prevent relative rotation between the spindle of the rewind apparatus and the reel, the latter is provided with a noncircular opening for the reception of the rewind spindle, and in this drawing the central opening has been designated by reference numeral 15 and has been indicated as being substantially rectangular and provided with outwardly extending projections 16. The spindle that cooperates with the reel is formed so as to fit the opening and therefore 30 relative rotation cannot take place. The strain produced by the rewind apparatus is usually sufficient to very quickly wear away the aluminum of which the hub members or side plates are made, but by applying to the inside of each hub 35 member a steel plate 13, this steel plate resists the force produced by the operation of the rewind apparatus and prevents the rapid wear that would otherwise take place if the aluminum hub members were left unreinforced. The rims 6 are 40 transversely concave as shown in Fig. 4 and the spokes 7 are also transversely concave as shown in Fig. 5, so as to give strength to the construction.

From the above description, taken in connection with the drawing, it will appear that the construction permits substantially all of the reel to be made from light aluminum, and by reinforcing the hub members or side plates 10 at the points where wear usually takes place, the advantage of 45 aluminum, as far as weight is concerned, can be retained and at the same time all the advantages of a heavy steel plate construction can be had as far as wear resisting properties are concerned.
